UNITED STATES PATENT OFFICE.

WILLIAM H. SARGENT, OF ST. LOUIS, MISSOURI, ASSIGNOR TO WAYNE MANUFACTURING COMPANY, OF ST. LOUIS, MISSOURI, A CORPORATION OF MISSOURI.

OPERATING MECHANISM FOR WASHING-MACHINES.

1,242,727.

Specification of Letters Patent.

Patented Oct. 9, 1917.

Application filed September 25, 1915. Serial No. 52,614.

To all whom it may concern:

Be it known that I, WILLIAM H. SARGENT, a citizen of the United States, residing at the city of St. Louis and State of Missouri, have invented a new and useful Operating Mechanism for Washing-Machines, of which the following is a specification.

This invention relates to improvements in operating mechanism for washing machines and consists in the novel design, arrangement and combination of the various parts and elements hereinafter more fully disclosed.

An object of the invention is to provide an operating mechanism preferably actuated by a power lever which will be simple, durable and inexpensive in construction and adapted in its specific embodiment for operating a washing machine of the pounder type, whereby the pounder is reciprocated vertically, a rotary movement being imparted to the pounder substantially at the end of each reciprocation of the pounder shaft.

Another object of the invention is to provide operating mechanism of the class described whereby the pounder shaft may be reciprocated vertically and given a rotary turn at a point substantially at the limit of the downward stroke effecting a rubbing operation of the clothes disposed between the pounder and the bottom of the tub, all of which is accomplished by application of a small amount of power to a power lever.

Another object of the invention is to provide a simple operating mechanism for imparting a reciprocating rotary and vertical motion to the pounder shaft mounted upon a hinged support.

With the foregoing ends, as well as additional advantages and features, in view I have designed, combined and arranged the various parts and elements as hereinafter more fully disclosed and specifically pointed out in the appended claims, reference being made in the course of the description to the accompanying drawings, in which—

Figure 1 is a side elevation of a washing machine illustrating an embodiment of the operating mechanism of the present invention.

Fig. 2 is a plan view of a washing machine in which the operating mechanism of the present invention is embodied.

Fig. 3 is a sectional view through the tub

of the washing machine, viewing the operating mechanism in side elevation oppositely from the illustration of the same mechanism in Fig. 1.

Fig. 4 is an end elevation of the operating mechanism, a portion of the power lever, connecting pitman and housing for the gearing being shown in cross section.

Fig. 5 is a plan view of a portion of the operating mechanism, certain parts being removed or cut through to show more clearly the arrangement of the parts.

Fig. 6 is a vertical section through the operating connection between the power shaft and the pounder shaft.

Fig. 7 is a plan view of a modified embodiment of the operating mechanism of the present invention, a portion of the gear casing being cut through and including, over the preferred embodiment, an additional speed increasing gear.

Fig. 8 is a side elevation of the modified form of the operating mechanism of the present invention.

Fig. 9 is an end elevation, a portion of the gear casing removed, of a modified embodiment of the present invention.

Fig. 10 is a section through the tub of the washing machine showing a side elevation of the operating mechanism of the modified form viewed from a point opposite the illustration thereof in Fig. 8.

In the embodiment of the invention illustrated in the drawings the tub 1 is mounted upon supports or legs 2, the bottom and side walls of the tub being corrugated interiorly as is usual in washing machines of this type. The tub is formed with a hinged cover 3. The cover 3 is provided with an opening substantially at the center thereof to accommodate the pounder shaft 4 which extends therethrough and upon the lower extremity of which is mounted a pounder 5 of familiar and known construction. The pounder 5 in order to increase its efficiency for agitating the clothes is provided with a series of removable wings 6.

A bracket 7 is mounted on the upper face of the cover, which bracket is designed to support the entire operating mechanism as well as to constitute a guide way for the shaft 4. A yoke piece 8 which is an integral part of the bracket 7 is provided at its extremities with eyes 9 which are in axial aline-

ment with the opening through the cover 3, the shaft 4 extending therethrough and being guided and supported from lateral displacement thereby.

5 A power shaft 10 extends at right angles to the shaft 4 and is revolvably journaled in a bearing 11 formed integral with the yoke piece 8 and a bearing 12 formed in the upper portion of a standard 13 formed integral with the bracket 7, respectively. The shaft 10 carries a crank arm 14 at its inner end, said crank arm being attached to a rack 15 by a pin 16. The rack 15 is mounted in a housing comprising horizontal plates 17 and 18. The rack 15 has vertical flanges 19-19 which operate in grooves formed in the plates 17. A bifurcated clevis 20, having axial openings therein through which the shaft 4 extends, is formed integral with the plate 19 of the housing. A segmental rack 21 has a hub 22 through which the shaft 4 extends. The rack 21 is adjustably secured to the shaft 4 by a set screw 23 mounted in the hub 22. The rack 21 is disposed between the two leaves of the clevis 20, said rack extending through a slot 24 in the plate 18 and meshing with the rack 15. The construction just described is best illustrated in Figs. 5 and 6 of the drawings.

30 The vertical plate 18 bears against a face of an oblong member 25 formed integral with the bracket 7 and supported transversely of the yoke 8, thereby supporting the housing and causing the same to operate without vibration.

40 It is preferable to provide a shield or guard 26 which in the embodiment shown is in the form of a semicylindrical grid attached by suitable binding devices to the member 25. The guard 26 prevents the clothes being placed in or taken from the tub from becoming engaged with the segmental rack 21, and also prevents injury to the operator.

45 The power shaft extends through the bearing 12 to the outer edge of the top of the machine and, in the embodiment shown in Figs. 1 to 6 inclusive, has a gear wheel 27 attached thereto. The gear wheel 27 is preferably of the open spoke type and is operatively connected by an eccentrically attached pitman 28 to a power lever 29 which is fulcrumed at its lower end to a bracket 30 mounted on the cover 3 of the machine. A balance wheel 31 mounted upon a shaft 32, which is journaled in a bearing portion 33 of the bracket 7, is operatively connected with the gear wheel 27 by a pinion 34 rigid on the shaft 32. The gear 27 is guarded by a gear housing 35 to prevent the accidental entanglement of clothes being placed in or removed from the tub, or injury to the operator.

55 60 65 The embodiment of the invention shown

in Figs. 7 to 10 inclusive is substantially the same as that illustrated in the other figures above described, except that the power shaft 10 carries in the place of the gear 27 a gear 36 which is in mesh with a gear 37 mounted on a stud shaft 38 journaled in a bearing portion 39 of the bracket 7, said gear 37 being in mesh with the pinion 34 of the balance wheel 31 arranged as above described.

70 75 80 85 90 95 In this embodiment power is applied from the power lever 29, through the pitman 28 to the gear 37, the gear 37 in turn driving the gear 36 on the power shaft at increased speed. This construction while the same in principle permits the acceleration of the operation of the power shaft and is preferred where a high speed machine is desired.

95 100 105 110 115 From the foregoing it will be understood that the operation of a washing machine embodying the present invention results in a new mode of treatment of the clothes in cleansing operations. As the power shaft 10 is continuously rotated by the operation of the power lever through the power connection described, the crank arm 14 will reciprocate the rack 15 and also raise and lower the rack housing which is operatively connected to the pounder shaft. As the rack 15 slides laterally at the upper and lower are of the cycle described by the crank arm, a rotary movement is imparted to the pounder shaft substantially at the end of the up and down stroke of the shaft. Thus, in addition to the agitation of the clothes effected through the vertical movement of the pounder, when the pounder has descended nearly to the limit of its downward stroke a rotary turn or twist will be imparted to the clothes disposed beneath the pounder, effecting a rubbing action against the bottom and sides of the tub. As the pounder shaft is adjustable vertically it may be selectively adjusted to accommodate it to different loads of clothes to regulate the extent of the rubbing action thereon. The rubbing action will also be effected upon the up stroke of the pounder as a reciprocation in a rotary direction occurs near the end of both the up and down stroke of the pounder, as above explained.

120 125 130 135 140 In practice the interrupted rotary motion developed by the mechanism of the present invention has been found to attain results which are superior to the results obtained by the forms of driving mechanism in which the rotary movement is substantially continuous throughout the vertically reciprocating stroke of the pounder, in that the rubbing action of the pounder is greater and for the further reason that the wrapping of the clothes around the pounder is to a large degree prevented. A machine, therefore, embodying the present invention is more efficient in cleansing the clothes and can be 130

operated with greater facility inasmuch as it is unnecessary to interrupt the operation of washing for the purpose of disengaging the clothes which become entangled with the 5 pounder in such machines as employ a vertical reciprocation in combination with a uniform rotary movement of the pounder.

I am aware that the principle of the 10 present invention may be embodied in other modified forms and that details in construction and design may be changed without in the least departing from the spirit and scope of the invention as set forth in the appended 15 claims. I do not desire to limit myself therefore to the exact construction shown and described, but what I claim and desire to secure by Letters Patent is:—

1. In an operating mechanism for washing machines, the combination with a support, 20 of a vertical shaft mounted in said support for axial and rocking movements, a power shaft journaled at right angles to the vertical shaft, drying mechanism for the power shaft, a crank attached to the power 25 shaft, and an intermeshing gear and rack wholly supported by the vertical shaft engaged and operated by the crank for moving the vertical shaft axially and rocking the vertical shaft near each end of its axial 30 movement.

2. In an operating mechanism for washing machines, the combination with a hinged support, of a shaft mounted in the support for axial and rocking movements, a power 35 shaft journaled at right angles to the vertical shaft on said hinged support, driving mechanism for said power shaft carried by the hinged support, a crank attached to the power shaft, and intermeshing gear and 40 rack elements wholly supported by the vertical shaft connecting said crank and the vertical shaft for imparting axial and rocking movements to said vertical shaft by rotation of said power shaft in one direction.

45 3. In an operating mechanism for washing machines, the combination with a support, of a vertical shaft mounted in said support for axial and rocking movements, a power shaft carried by said support, manually operable driving mechanism for said power shaft, a crank attached to said power shaft, a housing attached to the vertical shaft, a rack mounted in said housing and engaged by said crank, and a gear attached 50 to the vertical shaft meshing with the rack.

55 4. In an operating mechanism for washing machines, the combination of a hinged support, a bracket carried by said support, a vertical shaft extending through said support and journaled in said bracket for axial and rocking movements, a power shaft carried by said support, manual mechanism for rotating said power shaft, a balance wheel entrained with said power shaft, a crank attached to said power shaft, a rack engaged 60

by said crank, a gear on the vertical shaft in mesh with said rack, and a support for said rack attached to said vertical shaft.

5. In an operating mechanism for washing machines, a stationary support, a support hinged to said stationary support, a vertical shaft carried by said hinged support for axial and rocking movements, a power shaft carried by said hinged support, a lever pivoted to said hinged support, a gear wheel attached to said power shaft, an additional gear wheel in mesh with the one on the power shaft, a rod connecting the additional gear wheel with said lever, a small pinion in mesh with said additional gear wheel, a balance wheel in connection with said pinion, a crank arm attached to the power shaft, a rack connected to said crank arm, a support on said vertical shaft in which said rack is carried for movement with said vertical shaft, and a gear attached to the vertical shaft in mesh with said rack. 70 75 80

6. In an operating mechanism for washing machines, the combination of a stationary support having a horizontal wall, a support hinged to the stationary support above the horizontal wall, a vertical shaft extending through said hinged support, bearings in which said shaft is mounted for axial and rocking movements, a power shaft, manual mechanism for rotating said power shaft, a balance wheel entrained with said mechanism, a crank attached to said power shaft, and intermeshing gear and rack devices wholly supported by the vertical shaft actuated by the movement of said crank for moving said vertical shaft axially and rocking said vertical shaft in said bearings. 90 95 100

7. In an operating mechanism for washing machines, the combination with a hinged support, a vertical shaft mounted in said hinged support, a power shaft carried by said hinged support and disposed at right angles to said vertical shaft and spaced therefrom, and a connection between said power shaft and said vertical shaft comprising a housing adjustably and releasably attached to said vertical shaft, a reciprocating rack in said housing, and a gear segment within said housing in mesh with said reciprocating rack, substantially as specified. 105 110

8. In an operating mechanism for washing machines, the combination with a hinged support, a vertical shaft mounted in said hinged support, guides for supporting said vertical shaft in alinement, a power shaft journaled in a bracket and carried by said hinged support, driving mechanism for said power shaft for imparting a continuous rotary motion thereto, a member longitudinally adjustable of said vertical shaft, a guide bracket for said member, a gear segment secured to said vertical shaft within said member, a reciprocating rack in said member in mesh with said gear segment, and 120 125 130

a crank arm attached to said reciprocating rack and driven by said power shaft, substantially as specified.

9. The combination with a support, of a horizontal power shaft carried by said support, a lever pivoted to said support, connections actuated by said lever for rotating said power shaft, a balance wheel entrained with said connections, a shaft carried by 10 said support at right angles to said power shaft for axial and rocking movements, a crank arm attached to said power shaft, a rack engaged by said crank arm, a support connected to said second-mentioned shaft in 15 which said rack is mounted, and a gear attached to said second-mentioned shaft in mesh with said rack.

10. In an operating mechanism for washing machines, the combination with a power shaft and driving mechanism for imparting a continuous rotary movement thereto, of a vertical shaft at right angles to the power shaft, a crank arm attached to the power shaft, a gear attached to the vertical shaft 25 and movable axially therewith, and a rack engaged and operated by said crank and meshing with said gear for imparting axial and rocking movements to said vertical shaft.

11. The combination with a support, of a horizontal power shaft carried by the support, a lever pivoted to the support, con-

nnections actuated by the lever for rotating the power shaft, a balance wheel entrained with said connections, a shaft carried by the support at right angles to the power shaft for axial and rocking movements, a crank attached to the power shaft, a rack engaged by said crank, a housing connected to said second mentioned shaft supporting said rack, a gear attached to the second mentioned shaft in mesh with said rack, and a device for guiding said housing in a vertical plane during the axial and rocking movements of said second mentioned shaft. 45

12. In an operating mechanism for washing machines, the combination with a power shaft and driving mechanism for imparting a continuous rotary movement thereto, of a vertical shaft at right angles to the power shaft, a crank arm attached to the power shaft, a gear attached to the vertical shaft and movable axially therewith, a rack engaged by said crank meshing with said gear for imparting rocking movements to said vertical shaft, and a housing carried by said vertical shaft for supporting said rack. 55

In witness whereof, I have signed this specification in the presence of two subscribing witnesses.

WILLIAM H. SARGENT.
